BEAM CENTERING DEVICE FOR
CATHODE-RAY TUBESRichard B. Gethmann, Bridgeport, Conn., as-
signor to General Electric Company, a corpora-
tion of New York

Application May 21, 1948, Serial No. 28,315

3 Claims. (Cl. 250—161)

1

My invention relates to cathode ray tubes of the type which are used in television receivers and has for its object to provide a beam centering device which is simple in adjustment and construction.

In cathode ray tubes which are used in television receivers, it is customary to employ a device for focussing the cathode ray beam and an additional device for deflecting the beam through transverse paths for scanning fluorescent end walls provided in such tubes. In order that a televised scene being reproduced on the end wall of a cathode ray tube be accurately centered on that end wall and that distortion of the picture be minimized, it is desirable that the cathode ray beam itself be accurately centered relative to the axis of the tube. Where the centering force is applied to the beam prior to the focussing force, it has been found that a distortion is produced around the edge of the reproduced screen which is known as "neck shadow." Consequently, it has been found best to effect centering of the cathode ray beam subsequent to the application of focussing forces. Attempts have been made to effect centering of the beam at the time that deflection forces are applied to the beam, such centering action being obtained either by introducing the uni-directional component to the current supplied to the coils of the deflection yoke, or by mechanical adjustment of the position of the beam focussing device. It is an object of my invention to provide a new and improved beam centering device which applies beam centering forces to an electron beam subsequent to the application of focussing forces thereto and prior to the application of deflecting or scanning forces.

It is still another object of my invention to provide a new and improved beam centering device which employs a plurality of magnetic fields of uniform cross section and which are adjustable relative to each other to effect accurate centering of the electron beam.

One of the features of my invention consists in employing two permanent magnets having high directional characteristics and adapted to provide a magnetic field of uniform cross section across a narrow portion of the neck of the cathode ray tube. One of the magnets is adjustable in position relative to a magnetic shunt to control the strength and direction of the centering force.

The features of my invention which are believed to be novel and patentable will be pointed out in the claims appended thereto. For a better understanding of my invention reference is made to the following description and the accompany-

2

ing drawings in which Fig. 1 illustrates a cathode ray tube suitable for use in a television receiver and employing my invention; Fig. 2 is an enlarged view, partly in section, of my improved beam centering device; Fig. 3 is a view of one of the components of the device of Fig. 2; Fig. 4 is a side elevational view, partly in section, of a modification of my beam centering device; Figs. 5 and 6 are views illustrating certain components of the device of Fig. 4; and Figs. 7 and 8 are views illustrating additional modifications of my invention.

Referring now to Fig. 1, I have there illustrated a conventional cathode ray tube 1 suitable for use in a television receiver and comprising an evacuated envelope having a neck portion 2 and a fluorescent screen or end wall 3. The cathode ray tube 1 includes a cathode 4, a control electrode 5 and an accelerating electrode 6. Surrounding the neck portion 2 is a piece of tubing 7 formed of any suitable material which is mechanically secured to a deflection yoke 9 and upon which is positioned a focus coil 8. The focus coil 8 may comprise either an electromagnet or a combined structure including both a permanent magnet and an electromagnet, the current through which may be adjusted to control the focussing effect upon the cathode ray beam of the tube. The deflection yoke 9 may consist of a plurality of coils (not shown) for deflecting the cathode ray beam in both horizontal and vertical directions to scan the fluorescent screen 3 in the usual manner. Positioned between the focus coil 8 and the deflection yoke 9 is a beam centering device comprising a non-magnetic sleeve 10 having a longitudinal slot 11 therein. Supported on the sleeve 10 are a pair of ring-shaped permanent magnets 12, 13.

The construction of the beam centering device may be more clearly seen in the enlarged view of Fig. 2. The focus coil 8 includes an end plate 14 formed of steel or any other suitable ferromagnetic material having a neck 15 which engages the outer surface of the tube 7. Positioned between the sleeve 10 and the tubing 7 is a spacer 16 which supports sleeve 10. One end of sleeve 10 is arranged to slide over neck 15 of the end plate of the focus coil. The end of sleeve 10 remote from end plate 14 has a groove 17 which receives the peripherally incomplete permanent magnet 13. The adjacent ends of the magnet 13 are bent inwardly to engage slot 11 in the end of sleeve 10. Permanent magnet 12, for reasons to be pointed out later, is larger than magnet 13 and likewise has inwardly turned ends which fit into slot 11.

Magnets 12, 13 preferably are formed of any suitable permanent magnet material having a

high directional characteristic so that they provide a substantially uniform field between their opposite sides. This may best be explained by reference to Fig. 3 which is a side view of permanent magnet 12. The lines of force provide a uniform field across the area enclosed by the ring. The magnets 12 and 13 may be of rectangular cross section or they may be formed of a round magnetic wire. While I have found that magnetic materials of the copper-nickel-iron alloy type, known as cunife, are well adapted for use as the rings 12, 13, other magnetic materials, such as the copper-nickel-cobalt alloys including cunico, and the silver-manganese-aluminum alloys including silmanal, are also well adapted for use in this construction. Similarly, certain sintered type of permanent magnet materials may be employed. Fig. 3 also illustrates the manner in which the free ends of rings 12 and 13 are bent inwardly so that they fit within the slot 11. The ring 13 preferably is located in groove 17 and is cemented therein. The groove 17 preferably is located as close to the deflection yoke 9 as is practical. In using the beam centering device, the assembly of rings 12, 13 and the sleeve 10 is free to rotate about the neck portion 2 of the cathode ray tube and likewise about the neck 15 of the end ring 14. The neck 15, which is formed of iron or a suitable ferromagnetic material, acts as a shunt for the magnet 12 when the magnet is located in the position shown in Fig. 2. Since, however, a shunt such as the neck 15 is never a perfect shunt for all the magnetic flux, the magnet 13 is provided and is so magnetized that it provides a flux which is adjusted both in field strength and direction to produce a deflection of the cathode ray beam in a direction opposite to that produced by the shunted permanent magnet 12. Moreover, the strength of ring 13 is sufficient in magnitude approximately to balance out the deflection produced by magnet 12 when shunted by neck 15.

If ring 12 is moved axially of the cathode ray tube in the direction of ring 13, the shunting effect of neck 15 is lessened in such a manner that, when ring 12 is adjacent ring 13, the electron beam is deflected a predetermined amount from the tube axis, for example one inch from the tube axis. Thus, by adjustment of the axial position of ring 12 and by rotation of the assembly including rings 12, 13 and sleeve 10, the center of the television picture may be moved to any point within a one-inch circle. This range has been found sufficient to give the centering range required in television receivers.

In Fig. 4, I have shown a modification of my beam centering device which is particularly useful for centering the cathode ray beam of a tube in which there is a very small amount of space available between the focus coil 8 and the deflection yoke 9 for locating the beam centering device. In such a case, it is impossible to obtain the degree of control of beam centering which is possible with the arrangement of Fig. 2 in which the magnet 12 may be moved a considerable distance axially of the magnetic ring 13. In the arrangement of Fig. 4, there is provided a metallic non-magnetic sleeve 18 which is adapted to slip over the neck 15 at the end of the end ring 14 of the focus coil. The metallic sleeve 18 is provided on its periphery with a pair of diametrically positioned outwardly protruding portions 19. Adjustably supported for axial movement along the outer surface of the sleeve 18 is a first ring-shaped permanent magnet 21 and

rigidly secured within the inner surface of sleeve 18 is a second ring-shaped permanent magnet 22. Magnet 22, which may be a solid ring or may be split as illustrated, is located at the edge of sleeve 18 nearer the deflecting yoke. The sleeve 18 is likewise provided with a pair of laterally extending tabs or ears 23 which assist in rotating the sleeve and its supported magnets relative to the neck 15 and the neck portion of the cathode ray tube.

A centering device constructed as shown in Fig. 4 provides increased control of the field for centering a cathode ray beam in that the magnet 21 is removable and may be rotated through an angle of 180° to a position in which the magnetic flux thereof is aiding the flux established by magnet 22. In the use of the device of Fig. 4, the neck 15 functions as a magnetic shunt for the permanent magnet 21. The degree of shunting action obtained depends upon the extent to which the sleeve 18 telescopes neck 15 and the position of magnet 21 relative to the right-hand edge of sleeve 18. By adjusting the position of sleeve 18 relative to neck 15, more or less shunting of the magnetic flux magnet 21 is obtained. By adjusting the position of magnet 21 relative to magnet 22, the strength of the magnetic field within the neck of the cathode ray tube is controlled. Finally, by rotating the entire assembly comprising sleeve 18 and magnets 21, 22, the angular position of the cathode ray beam may be varied.

Fig. 5 is a side elevational view of permanent magnet 21 and illustrates the uniform magnetic field established in one direction across the cathode ray tube neck by that magnet. Fig. 6 is a side elevational view of the ring-shaped magnet 22. This magnet preferably is secured within the end of inner surface of sleeve 18 by cementing or soldering thereto. The magnetic flux of magnet 22 normally is of a polarity opposite to that established in the neck of the cathode ray tube by magnet 21. However, as explained previously, the free ends of magnet 21 may be spread apart slightly and the magnet rotated through 180° to establish a magnetic field which aids that established by magnet 22.

In Fig. 7 I have shown another modification of my invention in which two permanent magnet centering rings are mounted so that they may be rotated one with respect to the other. In the centering ring shown in this figure, one of the rings may be fixed on a supporting sleeve and the other ring may be adjustable axially of the supporting sleeve and may also be rotatable on the sleeve. Thus, as illustrated, the permanent magnet ring 24 may be fixed on the non-magnetic supporting sleeve 25, while the permanent magnet ring 26 is movable axially of sleeve 25 and is rotatable on that sleeve. By axial movement of ring 26, the shunting effected by the ferromagnetic end ring may be controlled. In this construction, the deflecting field is the vector sum of the two fields established by rings 24, 26. When these fields are opposing and equal in magnitude, no deflection of the electron beam results in the cathode ray tube whose neck is encircled by this structure. When, however, the fields of rings 24, 26 are aiding, a maximum deflection of the cathode ray beam is obtained. By rotating the two rings as a unit by rotation of the sleeve 25, control of the direction of the resultant deflecting force is obtained.

In Fig. 3, I have shown a still further modification in which a first permanent magnet ring 27

is supported upon and preferably fixed, as by cementing, to a non-magnetic supporting sleeve 28, while the second permanent magnet ring 29 is arranged concentric and coplanar with ring 27. The ring 29 is provided with tabs 30 by means of which it may be rotated relative to ring 27. A non-magnetic sleeve 31 may be positioned between rings 27, 29 if desired. In this construction, when the rings 27, 29 have the same field strength, a non-magnetic shunt, such as the shunt 15 illustrated in connection with the embodiment of Fig. 7, is not required. In using a beam centering device of the type illustrated in Fig. 8, the deflecting field is the resultant or vector sum of the fields established by rings 27, 29. This is a maximum when the fields are aligned and is zero when the fields are opposed. Preferably, the whole assembly is rotatable relative to the neck of a cathode ray tube by rotation of sleeve 28. Accordingly, by rotation of ring 29 relative to ring 27, the deflecting field may be fixed both in strength and in direction.

An important advantage of my improved beam centering device is that it may be permanently adjusted to provide optimum centering of the cathode ray beam of a particular cathode ray tube. Moreover, the centering effect established is permanent in character and eliminates the necessity of using either electrical centering controls which vary the unidirectional current in the coils of a deflection yoke, or of providing a complex mechanical system for adjusting the focus coil relative to the neck of a cathode ray tube. It is well known that mechanical devices which are used for adjusting the position of a focus coil relative to the neck of a cathode ray tube usually introduce distortion effects. These effects are particularly noticeable and objectionable if a composite focus coil is used in which focussing effects are obtained by both a permanent magnet structure and an electromagnet.

While, in the foregoing, I have described my improved beam centering device as being applied to a cathode ray tube of the type which employs electromagnetic focussing and deflection means, it is apparent that the invention is applicable equally as well to cathode ray tubes which use electrostatic focussing and electrostatic deflecting means. Accordingly, it will be understood that I do not wish to be limited to the particular embodiments shown, since various modifications may be made, and I contemplate by the appended claims to cover any such modifications as fall within the true spirit and scope of my invention.

What I claim as new and desire to secure by Letters Patent of the United States is:

1. A beam centering device for a cathode ray tube of the type having a neck portion through which the cathode ray beam is projected comprising a supporting sleeve, a pair of circular permanent magnets supported on said sleeve, each of said magnets being of the type producing a

uniform magnetic field parallel with a diameter thereof, said fields produced by said magnets being parallel, one of said magnets being fixed relative to said sleeve, a circular magnetic shunt slidable within said sleeve, the other of said magnets being movable axially of said sleeve to vary the position thereof relative to said first magnet and said shunt.

2. A beam centering device for a cathode ray tube of the type having a neck portion and means for projecting a cathode ray beam axially of said neck portion comprising, a non-magnetic supporting sleeve adapted to encircle the neck of a cathode ray tube, a pair of peripherally incomplete ring-shaped permanent magnets supported on said sleeve, said magnets producing parallel uniform magnetic fields across said sleeve in a direction normal to the axis thereof, the field of one of said magnets having a polarity opposite to that of the other, a first of said magnets being attached to said sleeve in a predetermined position axially thereof, the other of said magnets being movable axially of said sleeve, said sleeve and other magnet having portions resisting rotation of said other magnet relative to said sleeve, and magnetic means extending within said sleeve for shunting a variable amount of the flux of said other magnet as the position of said other magnet is varied axially of said sleeve.
3. A beam centering device for a cathode ray tube of the type having a neck portion through which the cathode ray beam is projected comprising a supporting sleeve, a pair of circular permanent magnets supported on said sleeve, each of said magnets being of the type producing a uniform magnetic field parallel with a diameter thereof, one of said magnets being fixed relative to said sleeve, a circular magnetic shunt slidable within said sleeve, the other of said magnets being movable axially of said sleeve to vary the position thereof relative to said first magnet and said shunt.
